ALTERNATING ACTION POLISHING MACHINE

Bela De Nagy, New York, N. Y.

Application March 24, 1934, Serial No. 717,243

5 Claims. (Cl. 15—49)

This invention relates to polishing and brushing machines, as described in my copending application, Serial No. 670,733, filed May 12th, 1933, and has for its main object to provide a machine 5 wherein both the polishing and brushing means will be carried simultaneously, said machine being adapted to be used either as a polishing or brushing machine without any exchange of the parts.

Still a further object of my invention is to 10 provide a machine, as characterized hereinbefore, which will have means incorporated therein whereby one set of operative devices, like those used for polishing operations may be put into active position while another set of operating devices, like those used for brushing operations will 15 be made inactive, or vice versa, so that the machine may be used alternatively for brushing or polishing operations, as desired. It will be obvious that based on the same principle a machine 20 may be built which will be adapted for more than two alternating operations in case the same may be desired to be used for some other kind of relating operation aside of brushing or polishing.

Other objects of this invention will be apparent 25 as the specification of the same proceeds.

In the drawings forming a part of this specification and accompanying the same:

Fig. 1 is a plan view of my assembled machine, 30 a part of the same being broken away and shown in section;

Fig. 2 is a sectional elevation of my assembled improved machine, the section being taken on the line 2—2 of Fig. 1;

Fig. 3 is a bottom view of my novel machine, 35 while

Fig. 4 shows a circular cylindrical section of my device, generally on the lines 4-4 of Fig. 2, said cylindrical section being shown in an imaginary developed or flattened condition in a fragmentary 40 manner;

Figs. 5 and 6 are a plan view and a side elevation, respectively, of a slidable brush used in my device.

Referring now to the drawings more closely, by 45 characters of reference, my invention is provided with a housing 10 having an upper compartment 11 and a lower compartment 12 and a partition wall 13 between said two compartments, said housing being generally of a cylindrical shape 50 and placed in a vertical position when used in my invention. In the upper compartment 11 of the housing, a rotor or turbine 14, having a plurality of vanes 15, is arranged on a rotating disc 14a and terminated by outer and inner imaginary cylinder 55 surfaces 16 and 17, respectively, as is well known

in the art. The contour of the vanes 15 may be designed according to the principles of engineering science to be most efficient for the conditions present in the particular case, but for the sake of simplicity and saving, I prefer to make them circular segments. A hub 18 is also provided for the rotor 14 by which the same is secured on a vertical shaft 19. A removable cover 21 may be provided for the housing 10 and in the center thereof may be arranged a ball-bearing, generally 10 indicated by the numeral 22 for the upper end of the shaft 19.

A second ball-bearing 23 may be provided on the partition 13, shaft 19 projecting through said second ball-bearing 23 and the lower end 24 of 15 said shaft may carry in a removable and exchangeable manner the operating device proper 25 secured thereon. Said operating device is shown in this embodiment of my invention as a rotating frame 26 slidably secured to the lower 20 end 24 of the shaft 19, as shown in Fig. 2 but not described in this specification more in detail, since it will be understood by those versed in this art and since it is not needed to be detailed for the purposes of this application. Said frame 26 25 is pressed downwardly towards the floor 27 by the spring 28 as will be understood and as has been more fully explained in my copending application mentioned hereinbefore. The operating devices proper of my machine are arranged in 30 said frame 26, as will be more fully explained hereinafter.

The upper compartment 11 of the housing 10 is continued in an air conduit 32 through which compressed air or other gas may be introduced, 35 as indicated by the arrow 33, from any suitable source, with a pressure and velocity as desired. For a convenient and easy use of my invention said conduit 32 may be provided with means whereby it may be attached to an outlet opening 40 on the usual vacuum cleaner and my device operated therethrough.

The air will follow the internal contour of the air conduit 32 (Fig. 1) and will strike the vanes 15, as at 34, will then pass through them in a 45 certain case, that is, at a certain speed, pressure and other factors of operation, following the direction generally indicated by the dot and dash line 35 and leaving the inner openings of the vanes at 35a will pass through the space in the rotor following the line 36 and will exit following the center line 37 striking the vanes once more at the opposite side of the rotor so that the same air current will act on the vanes a second time. 50 For the exit of the air openings 39 are provided 55

in the wall of the compartment 11 (Fig. 2) substantially opposite to the conduit 32 and being spread at that portion of said wall to a certain distance, as has been shown more in detail in my 5 copending application.

The wall of the lower compartment 12 of the housing 10 extends outwardly, as at 44, and is continued in an outer second downwardly projecting wall 45, the lower portion 46 of the wall 10 of the compartment 12, the outwardly projecting extension 44 thereof, and the outer wall 45 forming a circular downwardly open channel 47. A lining member 48 is secured in said channel 47, said lining member in this embodiment being 15 shown as made of wood but, of course, it may be made of any other suitable material, like a metal stamping or casting. A plurality of slideable downwardly turned bristle or felt brushes, generally of the construction indicated in Figs. 20 5 and 6, are arranged in said lining piece 48, for the purpose of supporting my machine on the floor 27, by resting on said brushes, as has been explained more in detail in my copending application mentioned hereinbefore. Each of said 25 resting brushes has an upper frame member 49, generally of an oval contour and following the curvature of the center circle of the channel 47, the active brush or felt part 50 being secured into said upper frame 49, which is shown in this embodiment as made of wood but which, of course, may be of any other material and any other suitable construction, as will be understood by those versed in this art.

In the embodiment of my device shown in the drawings I employ three bristle brushes for resting my device thereon, said bristle brushes being indicated by the numerals 51, (Figs. 2, 3 and 4) and I also employ three felt resting devices indicated by the numerals 52, all of these resting 35 devices being slideable upwardly and downwardly in appropriate openings in the lining piece 48. Each brush or felt device also has an upstanding central wedge 53 secured thereon in the design shown in Figs. 5 and 6 and a complete circular 40 slot 54 is provided in the upper central portion of the lining piece 48 in which said wedges 53 may be guided in an upwardly and downwardly 45 sliding manner.

A circular depression 55 is also provided in the 50 top part of the lining piece 48 in which depression is arranged a circular ring 56 slideable therein in a circular manner.

The bristle and the felt brush devices 51 and 52 are arranged alternatingly and preferably in 55 pairs opposite one another, as shown in Figs. 3 and 4, their wedges 53 being oppositely turned towards one another, and a similar but down-hanging wedge 57 is secured on the rockably slideable ring 56 between each pair of bristle and felt 60 devices 51 and 52, said downhanging wedge 57 being double acting to co-operate with either of the wedges 53 at the two sides thereof upon a right hand or left hand rocking of the ring 56, as will be obvious, and said downhanging wedges 65 57 are also adapted to play in said center slot 54 of the lining piece 48. In the rear of the machine the ring 56 will have a boss 58 to which is secured a handle device 59 operating in a slot 60 so that when the handle 59 is moved in a right handed 70 or left handed direction through the slot 60 the ring 56 will describe the same movement and will cause the double acting wedges 57 to engage either all the wedges on the bristle devices or all the wedges on the felt devices and in the first 75 case all the bristle devices will be pushed down-

wardly, while all the felt devices will be permitted to ride upwardly, as shown in Fig. 4, while in the second case the play of the bristle and the brush devices will be the reverse. All the bristle and brush devices are normally pressed upwardly by the springs 61 playing in holes 62 and pressing against a separate bottom plate 63 secured to the lining piece 48.

In the operation of such machines it is sometimes desired to use them as brushes while at other times we want to use them as polishing machines. In case the machines are to be used as brushes, ring 56 will be turned in such a manner that the brush devices 51 will engage the floor 27 while the 10 felt devices 52 will be drawn up into an inactive 15 position, while in case the machine is to be used for polishing operations, ring 56 will be moved in an opposite direction, the felt devices will be made active and the bristle or brush devices proper will be permitted to be pressed upwardly in the machine into an inactive position by the spring 61, as will be obvious. Thus, I provide a machine which, without any exchange of parts and with a very simple regulation movement or operation of some of its parts, may be used either for brushing 20 or for polishing operations.

The actual brushing or polishing operation will be done by the central rotating operating part 25 of my device, as will be obvious, which may also have a plurality of bristle brushes proper 30 64 and felt devices 65 arranged in the frame 26.

It will be understood that changes and variations may be made in the parts and combinations of my device and I hereby reserve all my rights to any and all such changes as are within the 35 spirit of the invention and the scope of the appended claims.

What I claim as new, is:

1. In a brushing and polishing machine, a first set of elements for brushing operations; a second set of elements to be used for polishing operations, and means to simultaneously move said first elements into an active operative position and said second elements into an inactive position, of vice versa, said means including a frame structure for said machine, each element being arranged in said frame adapted to move upwardly or downwardly therein to a limited extent; a wedge carried by each element, tapering in the direction of the upward movement thereof, a movable wedge in said frame for each element tapering in the direction of the downward movement of said element, the tapering surfaces of each two respective wedges being adapted to engage each other in a gradually-increasing manner and thereby to cause the respective element to gradually move in a downward direction; means to move one set of wedges in the frame into increasing engagement with the wedges on the respective elements and to simultaneously move the other set of frame wedges into decreasing engagement with the wedges on the respective other elements, so as to cause one set of elements to move downwardly and permit the other set of elements to move upwardly, and means to automatically cause said other set of elements to move upwardly when said frame wedges are moved as described.

2. In a brushing and polishing machine, a first set of elements for brushing operations, a second set of elements to be used for polishing operations, and means to simultaneously move said first elements into an active operative position and said second elements into an inactive position, or vice versa, said means including a

- frame structure for said machine, each element being arranged in said frame adapted to move upwardly or downwardly therein to a limited extent; a wedge carried by each element, tapering in the direction of the upward movement thereof, a movable wedge in said frame for each element tapering in the direction of the downward movement of said element, the tapering surfaces of each two respective wedges being adapted to engage each other in a gradually increasing manner and thereby to cause the respective element to gradually move in a downward direction; means to move one set of wedges in the frame into increasing engagement with the wedges on the respective elements and to simultaneously move the other set of frame wedges into decreasing engagement with the wedges on the respective other elements, so as to cause one set of elements to move downwardly and permit the other set of elements to move upwardly, and a spring means normally pressing all said elements in an upward direction.
3. In a brushing and polishing machine, a first set of elements for brushing operations, a second set of elements to be used for polishing operations, and means to simultaneously move said first elements into an active operative position and said second elements into an inactive position, or vice versa, said means including a frame structure for said machine, each element being arranged in said frame adapted to move upwardly or downwardly therein to a limited extent; a wedge carried by each element, tapering in the direction of the upward movement thereof, a movable wedge in said frame for each element tapering in the direction of the downward movement of said element, the tapering surfaces of each two respective wedges being adapted to engage each other in a gradually increasing manner and thereby to cause the respective element to gradually move in a downward direction; means to move one set of wedges in the frame into increasing engagement with the wedges on the respective elements and to simultaneously move the other set of frame wedges into decreasing engagement with the wedges on the respective other elements, so as to cause one set of elements to move downwardly and permit the other set of elements to move upwardly, and means to automatically cause said other set of elements to move upwardly when said frame wedges are moved as described, the two wedges in a pair being oppositely placed, and the respective two wedges in the frame being in the form of a laterally movable double wedge for each pair adapted to engage the wedge on one element and disengage the wedge on the other element in the pair, or vice versa, on being moved to one direction or the other, said double wedges being secured on one movable member in said frame so as to be adapted to be moved therewith in either direction simultaneously.
5. In a brushing and polishing machine, a first set of elements for brushing operations, a second set of elements to be used for polishing operations, and means to simultaneously move said first elements into an active operative position and said second elements into an inactive position, or vice versa, said means including a frame structure for said machine, each element being arranged in said frame adapted to move upwardly or downwardly therein to a limited extent; a wedge carried by each element tapering in the direction of the upward movement thereof, a movable wedge in said frame for each element tapering in the direction of the downward movement of said element, the tapering surfaces of each two respective wedges being adapted to engage each other in a gradually increasing manner and thereby to cause the respective element to gradually move in a downward direction; means to move one set of wedges in the frame into increasing engagement with the wedges on the respective elements and to simultaneously move the other set of frame wedges into decreasing engagement with the wedges on the respective other elements, so as to cause one set of elements to move downwardly and permit the other set of elements to move upwardly, and means normally forcing all elements in an upward direction, said wedges when engaging a set of elements being adapted to force them in a downward direction against said spring means, said elements being arranged in pairs of the two sets, the two wedges in a pair being oppositely placed, and the respective two wedges in the frame being in the form of a laterally movable double wedge for each pair adapted to engage the wedge on one element and disengage the wedge on the other element in the pair, or vice versa, on being moved to one direction or the other.
6. In a brushing and polishing machine, a first set of elements for brushing operations, a second set of elements to be used for polishing operations, and means to simultaneously move said first elements into an active operative position and said second elements into an inactive position, or vice versa, said means including a frame structure for said machine, each element being arranged in said frame adapted to move upwardly or downwardly therein to a limited extent; a wedge carried by each element, tapering in the direction of the upward movement thereof, a movable wedge in said frame for each element tapering in the direction of the downward movement of said element, the tapering surfaces of each two respective wedges being adapted to engage each other in a gradually increasing manner and thereby to cause the respective element to gradually move in a downward direction; means to move one set of wedges in the frame into increasing engagement with the wedges on the respective elements and to simultaneously move the other set of frame wedges into decreasing engagement with the wedges on the respective other elements, so as to cause one set of elements to move downwardly and permit the other set of elements to move upwardly, and means to automatically cause said other set of elements to move upwardly when said frame wedges are moved as described, the two wedges in a pair being oppositely placed, and the respective two wedges in the frame being in the form of a laterally movable double wedge for each pair adapted to engage the wedge on one element and disengage the wedge on the other element in the pair, or vice versa, on being moved to one direction or the other.
